E. D. HOOKER

HOISTING APPARATUS

Filed Nov. 2, 1923

Fig. 1.

UNITED STATES PATENT OFFICE.

EDWARD D. HOOKER, OF NEW YORK, N. Y., ASSIGNOR TO GILLIS & GEOGHEGAN, INC.,
OF NEW YORK, N. Y., A CORPORATION OF NEW YORK.

HOISTING APPARATUS.

Application filed November 2, 1923. Serial No. 672,266.

To all whom it may concern:

Be it known that I, EDWARD D. HOOKER, a citizen of the United States, residing in the city of New York, borough of Manhattan, in the county and State of New York, have invented a certain new and useful Improvement in Hoisting Apparatus, of which the following is a specification.

This invention relates to hoisting machinery such as is used in sidewalk hoistways, and the like, and it has for its objects among others, to provide a simple and efficient hoisting device readily applied to the hoistway with the parts so arranged that the closure for the hoistway will be opened by direct contact therewith of opening means on which the hoisting head is mounted. The hoisting head is carried by vertically movable, bodily-movable, means in contradistinction to being carried by a telescopic support, issuing from a sustaining column at the bottom of the hoistway. The present improved hoisting apparatus of this general type comprises vertically-movable means guided at opposite sides of the hoistway, its upper end adapted to contact directly with the movably mounted closure, the hoisting mechanism or head being carried by such closure-opening means. The closure is arranged to return to its closed position by gravity. Another important object is to provide means for automatically engaging the closure and holding the same reliably in the open position.

Other objects and advantages of the invention will hereinafter appear and the novel features thereof will be specifically defined by the appended claims.

The invention in its preferred form is clearly illustrated in the accompanying drawings, which, with the reference numerals marked thereon, form a part of this specification and in which—

Figure 1 is a vertical section through a hoistway showing the present invention installed therein, in elevation.

Figure 2 is a horizontal section on the line 2—2 of Figure 1, looking in the direction of the arrow 2, the doors being omitted.

Figure 3 is a detail in elevation, looking in the direction of the arrow 3 in Figure 1.

Figure 4 is a horizontal section on the line 4—4 of Figure 3, looking in the direction of the arrow 4, and partly in plan view.

Figure 5 is an enlarged sectional detail of the guiding means shown at the left in Figure 2.

Figure 6 is a similar view showing the means for holding the doors in the open position.

Figure 7 is a vertical section, partly in elevation, showing a detail of the door-opening mechanism.

Like numerals of reference indicate like parts throughout the several views.

Referring to the drawings, 10 designates the hoistway, 11 the sidewalk level, and 12 the closure for the hoistway, in the present instance shown as composed of two doors hinged in any suitable manner, and adapted to assume closed positions by gravity when not held open by the means which carries the hoisting head, or otherwise.

13 is the metallic framing about the opening to the hoistway, to which the doors 12 are hinged, and may be understood to be of the usual or any approved construction.

Suitably secured within the hoistway, near the bottom of the same, as seen in Figure 1, is a bracket 14 fixedly fastened to the wall 15 of the hoistway and this bracket serves not only for the mounting of the mechanism for elevating the door-opening means but also as a guide for such means.

16 is a shaft supported in the bracket 14 and carrying a gear-wheel 17 which is in mesh with a pinion 18 on the shaft 19 also supported in the bracket 14. 20 is a crank on the shaft 19.

On the shaft 16 is a wheel 21 the periphery of which is provided with spurs 22 which are adapted to cooperate with the series of holes 23 in the long depending leg 24 of the arched hoist-supporting and door-opening member. As seen in Figures 1 and 4 the bracket 14 serves as a guide for this leg 24. The opposite shorter leg 25 of this hoist-carrying member is guided in a guide 26

mounted on the wall of the hoistway, as seen in Figure 1. The arched upper end 27 of the hoist-carrying member is designed to contact directly with the under side of the closure and raise the same as the said member is raised, and upon this member near its upper end beneath the arch is mounted the hoisting head which may be of any of the well known or approved forms. It 10 comprises the gearwheel 28 carried by a shaft 29 supported in the arms 30 of a frame carried by the vertical standard or the like 31 which is mounted to partially revolve in the bearings 32 on the bracket 33 fast to the flange 57 of the leg 24, all as seen in Figure 1. 34 is a drum indicated in dotted lines, on the shaft 29 upon which is wound a cable 35 carrying the hoisting hook 36. 37 is a pinion meshing with the gearwheel 28, said 20 pinion being mounted on the shaft 38 supported in the arms 30 and upon which the crank handle 39 is secured.

In order to guide the leg 24 at a point near the top of the hoistway and impart the 25 required rigidity thereto to sustain it in its movements and to enable it to withstand any strains put thereupon, the stem 40 of this leg has riveted thereto the angle irons 41 and 42, see Figures 2, 4, 5 and 6, and to the 30 framing 13 about the mouth of the hoistway is riveted at 43 the angled member 44 to the face of which are secured at 45 the members 46, the flanges 47 of which receive and serve as guides for the cooperating flanges 35 48 of the angle irons 41 and 42, all as seen in Figures 2 and 5.

49 is an angled member or guard having one limb 50 secured to the leg 24, and cooperating therewith is the guard member 51, 40 see Figure 2. The adjacent ends or edges of these two members overlap and constitute 45 guard gates disposed at the side of the hoistway at a right angle to the doors 12, as seen in Figure 1. The margin of the gate 51 opposite to that which overlaps the fixed 50 gate 49, is joined to the member 52 by a spring hinge connection 53, see Figure 2, the construction being such that the swing gate 51 will normally be closed against the fixed 55 gate 50 but readily yielding to force when the ash can or other load is placed thereagainst to move the same from the hoistway. The member 52 is secured to the short leg 25 in any suitable manner.

55 On the stem 54 of the short leg 25 and extending downwardly thereon from the spring of the arch a short distance, are angle irons 55 similar to those marked 41 on the long leg 24. As before stated the angle irons 60 41 serve with the member 44 and bracket 14 to guide the leg 24 in its vertical movements, and the angle irons 41 with the angle irons 55 perform the additional function of automatically holding the doors 12 in the verti-

cal open position. On the free margin of 65 each door, in line with the movements of the angle irons 41 and 55, are secured hook-like projections 56 adapted to overlap both the flanges of such irons and engage therewith as the doors are lifted and swing into the 70 vertical open position, and maintain such engagement during the period in which the doors remain open.

The parts being constructed and arranged substantially as above described, the operation, briefly stated is as follows:—Normally the doors 12 are closed and the hoist supporting member with its attached parts are in the dotted line position seen in Figure 1. When it is desired to use the hoist the operator grasps the crank handle 20 and turns the same to rotate the shaft 19, the pinion 18 meshing with the gearwheel 17 turns the wheel 21 and its spurs 22 engaging in the holes 23 in the leg 24 raises the latter with 85 the hoisting head. When the arch 27 strikes the doors the latter will be opened. When the parts have been raised a sufficient distance the same are stopped, being held against retrograde movement in any suitable manner, and the doors held stationary in the open position by the engagement of the angle irons 41 and 55 with the projections 56. Then the cable 35 and its hook 36 are lowered, the can or other object to be raised is 90 engaged with the hook, and the crank handle 39 turned to wind the cable upon the drum, and when the can is at the proper height the can is pushed against the guard gate 51, the latter opens, and as soon as the 95 can has passed through the opening the gate is closed by means of its spring hinge. The hoist is then lowered to the dotted line position in Figure 1, the doors 12 automatically closing.

100 It will be noted that the bucket hoisting mechanism carried by the upper end of the hoist-carrying member is entirely independent of and in nowise associated with the means for raising and lowering said member; furthermore, when the hoist-carrying member is raised to its operative position it is there retained until all of the hoisting has been done, and it is not necessary to raise and lower the hoist-carrying member 115 with each operation of raising and lowering the bucket.

Modifications in detail, proportion of parts etc., may be resorted to without departing from the spirit of the invention or 120 sacrificing any of its advantages.

I claim:—

1. In a hoisting apparatus, a hoistway closure, a vertically movable hoist-supporting member, adapted to contact directly with and open said closure, and a laterally openable guard gate carried by said member.

2. In a hoisting apparatus, a hoistway

closure, a vertically movable hoist-supporting member adapted to engage directly with and open said closure, and an outwardly swinging automatically closing guard gate carried by said member.

3. In a hoisting apparatus, a hoistway closure, a vertically movable hoist-supporting member adapted to contact directly with said closure to move it upward, and an out-

wardly swinging spring-closed guard gate 10 for the hoistway carried by said member.

4. In a hoisting apparatus a vertically movable hoist-supporting member, and an outwardly swinging spring-actuated guard gate carried thereby. 15

In testimony that I claim the invention above set forth I affix my signature hereto.

EDWARD D. HOOKER.
